(57) **CLAIM**

The ornamental design for a helmet flap cover, as shown and described.

DESCRIPTION

FIG. 1 is a perspective view of a helmet flap cover showing the new design;

FIG. 2 is a left side view of the helmet flap cover of FIG. 1;

FIG. 3 is a right side view of the helmet flap cover shown in FIG. 1;

FIG. 4 is a front view of the helmet flap cover shown in FIG. 1;

FIG. 5 is a rear view of the helmet flap cover shown in FIG. 1;

FIG. 6 is a top view of the helmet flap cover shown in FIG. 1; and,

FIG. 7 is a bottom view of the helmet flap cover shown in FIG. 1.

The broken lines in FIG. 1 illustrate unclaimed environment and form no part of the claimed design.
